UNITED STATES PATENT OFFICE

CHARLES A. RAYMAN, OF CHICAGO, ILLINOIS

PRINTER'S PROOF PRESS

Application filed December 17, 1930. Serial No. 503,038.

This invention relates to printers' proof presses for the purpose of taking off galley and job proofs before the type are locked in the regular presses or to produce finished 5 copies of price tags and show cards without locking in regular presses.

The principal object of the invention is to provide a proof press in which the paper or cardboard is automatically held and released upon the movement of the impression roller.

Another object of the invention is to provide manual means to release the paper independent of the roller releasing means.

Still another object of the invention is to provide extensible rods for arranging and holding the type in place.

With the above and other objects in view the invention consists in general of certain 20 novel details of construction and combinations of elements hereinafter fully described, illustrated in the accompanying drawings and specifically claimed.

In the accompanying drawings like characters of reference indicate like parts in the several views, and:—

Figure 1 is a top view of the proof press.
Figure 2 is a side view thereof.

Figure 3 is a section substantially on line 30 3—3 of Figure 1.

Figure 4 is an end view of the press.

Figure 5 is a section on line 5—5 of Figure 1.

Figure 6 is an assembled view on the extensible rod for holding the type in place.

Figure 7 is an end portion of the rod, and
Figure 8 is the movable end sleeve.

Referring now to the drawings in detail, numeral 1 designates the frame of the press 40 consisting of two side members 2 and 3 and joined together by the cross members 4 and 5. Mounted on the frame is a carriage 6 adapted to move the length thereof. The carriage includes an impression roller 7 journalled in the side plates 8, a flanged wheel 9 on one side of the roller running on a track 10 and a gear 11 on the opposite side of the roller meshing with a rack 12.

Embedded in the side member 3 as best 50 seen in Figure 5 is a movable gripping bar

13 for holding the paper 14 while making a proof copy. The means to operate the bar is as follows. Screwed in the underside of the bar are four studs 15 with the lower ends engaging the levers 16 keyed to the shaft 17. 55 Fastened to the ends of the shaft are handles 18 having near the bottom studs 19 screwed therein and supporting rollers 20. The end of the studs are formed with ears to which are fastened tension springs 21. 60 The lower end of the tension springs are attached to brackets 22. The pull of the tension springs will have a tendency to move the handles downwardly and revolve the shaft 17 anti-clockwise for the reason that 65 the handles are keyed to the shaft. This action will lift the studs 15 and bar 13 towards the track 10. As the edge of the paper 14 is disposed between the track and bar the paper will be firmly held against movement until it 70 is released.

There are two ways to release the paper after making the impression. One is by manually moving the end of the handle upwardly against the tension of the springs and 75 the other is by moving the carriage 6 so that the cam 23 of the bar 24 supported by the side plates 8 comes in contact with any one of the rollers 20 and lifts same. It will thus be seen that lifting the end of the handle manually or automatically by the aid of the cam 23 will move the bar 13 downwardly and release the paper. 80

The type 25 or other characters to be printed are placed on the bed plate 26 of the device and are held in the proper relation to each other by the extensible bars 27. The bars comprise a central member 28 having narrowed necks 29 at the ends on which fits the sleeves 30. Compression springs 31 are placed within the sleeves for urging the said sleeves outwardly. At the ends of the bars are studs 32 which ride in the slots 33 of the sleeves and prevent same from leaving the rods. 85 90 95

The base of the type are formed with grooves 25a at the sides for saddling the rods and thus prevent the type from working upwardly. When necessary clamps 34 may be used as shown in Figures 1 and 3 for keep- 100

ing the type parallel. The clamps are preferably made of sheet metal with the ends formed into hooks 35 for embracing the rods.

The operation of the device is as follows: The carriage 6 is first moved to one of the ends of the press as far as the stops 36 will permit. In this position the cam 23 will engage the rollers 20 and lift the handle 18 and pull the gripping bar 13 downwardly against the pull of the springs 21. The type 25 is then placed in the press and held in place by the rods 27 as shown in Figure 1 and then inked with an ordinary hand roller. Next the paper 14 to be printed is placed above the type with one of the sides above the gripping bar 13 and the carriage moved to the opposite end of the press so that the impression roller 7 will press the paper against the inked type and make an impression. Just as soon as the carriage is slightly moved the cam 23 will be dis-engaged from the rollers 20 and the gripping bar 13 will jump up against the paper as shown in Figure 5 and hold the paper against slipping. Except when the carriage is at the extreme ends against the stops 36 the paper will be held in place. To release the paper when the carriage is in the center of the press all that is necessary is to manually move one of the handles 18 upwardly. The extensible bars 27 rest on the ledges 37 in order to maintain the bars at the proper height and to be lined up with the grooves 25a of the type. The ledges 37 extend around the four sides of the frame so the bars 27 can also be positioned longitudinally. In this event longer bars will be used.

It will thus be seen that I have provided a simple and efficient proof press for the purpose specified. The paper gripping or releasing mechanism is controlled automatically by the movement of the press or can be manually controlled. The type is held in the proper relation to each other by the rods so as to avoid any accidental displacement.

It is obvious that many minor changes may be made in the form and construction of the invention without departing from the material principles involved. I do not, therefore, desire to confine the invention to the exact form herein shown and described, but I desire to include all forms which properly come within the scope claimed.

Having described my invention, I claim:

1. In a proof press of the class described, the combination of a frame, of a bed plate for supporting the type, a carriage arranged to move on said frame, means in said frame to grip the paper to be printed, and means to automatically release the gripping means when the carriage is moved to either end of said frame.

2. In a proof press of the class described, the combination of a frame, of a bed plate for supporting the type, a carriage arranged

to move on said frame, means in said frame to grip the paper to be printed, means to automatically release the gripping means when the carriage is moved to either end of said frame, and means to manually release the gripping means regardless of the position of the carriage.

3. In a proof press of the class described, the combination of a frame including two side members, a gear rack on one of the side members, a movable gripping bar embedded in the other of the side members, a carriage supported on said side members, said carriage including a gear meshing with said rack, and means to raise the gripping bar when the carriage is moved to one end of the frame.

4. In a proof press of the class described, the combination of two side members, of a carriage supported thereon, a cam at the bottom of said carriage, a gripping bar embedded in one of said side members, a set of studs attached to the said gripping bar, a set of levers attached to the ends of said studs, said levers keyed to a horizontally disposed shaft, handle members at each end of said shaft, a roller associated with each of said handle members, and springs for normally urging said rollers downwardly, said cams adapted to move said rollers upwardly and move said gripping bar downwardly.

5. In a device of the class described, the combination of two parallel side members, of a bed plate for supporting type, and a set of extensible rods for holding said type in place, a ledge for said rods, said rods made in several sections and having compression springs for urging the end sections outwardly against the sides of said parallel members.

In testimony whereof I affix my signature.

CHARLES A. RAYMAN.
